SAFETY REFLECTOR ASSEMBLY

Alan E. Brickman, Rostraver Township, Westmoreland County, Pa.

Application July 30, 1940, Serial No. 348,485

9 Claims. (CL 88—82)

This invention relates to safety reflectors for highways and particularly to an improved safety reflector assembly which is adapted to be attached to the highway guard rails of the cable type.

Safety reflectors are now in common use as an aid to the motorist for marking highways at various points, such as dangerous curves, the lateral limits of the highway, and the location of the guard rails. Usually such reflectors are mounted on the highway guard posts to which the guard rail is attached. While the reflectors positioned on the posts are generally satisfactory in most instances, they are not entirely satisfactory in their use in connection with rails of the cable type, in that the cables, being disposed in front of the posts, would oftentimes sag during the warm summer months of the year, and obstruct the line of vision between the motorist or those travelling along the highway and the reflectors thereby defeating the purpose for which they are intended.

Reflector buttons as used on highway guard rails have come into general use only in the past few years and difficulty has been encountered in applying reflector buttons properly to the guard rails then in use, for the reason that the top of the guard posts in most instances are flush with the top of the bracket which supports the guard rail thereby not providing sufficient space in the post for attaching the reflectors thereto. That is to say, such reflectors could neither be conveniently nor satisfactorily assembled on existing highway guard rails.

In the present invention, there is provided a safety reflector assembly in which the above disadvantages are eliminated and one which is visible from either direction of travel at all times and under any and all conditions.

Accordingly, it is one of the objects of the present invention to provide an improved safety reflector assembly for highway guard rails which is simple and inexpensive in its construction and application and, at the same time, one which can be easily and quickly applied to now existing guard rails.

It is another object of the invention to provide an improved safety reflector assembly for highway guard rails having a double or twin reflector lens which is adapted to aid those travelling in either direction along the highway.

It is a further object of this invention to provide an improved safety reflector assembly which can conveniently be applied at any point along the guard rail and at the same time, one which is 55

securely attached to the guard rail so as to prevent displacement of the same thereon.

Various other objects and advantages of this invention will be more apparent in the course of the following specification and will be particularly pointed out in the appended claims.

In the accompanying drawing there is shown, for the purpose of illustration, one embodiment which my invention may assume in practice.

10 In the drawing:

Figure 1 is a plan of a portion of a highway guard rail of the cable type showing the improved safety reflector assembly of my invention incorporated therewith;

Figure 2 is an elevation of Figure 1;

Figure 3 is a plan of the improved safety reflector assembly of my invention;

Figure 4 is an elevation thereof;

Figure 5 is a section taken on line V—V of Figure 4; and,

Figure 6 is a perspective of the safety reflector of the present invention showing it attached to the guard cable.

Referring more particularly to the drawing, the improved safety reflector assembly of my invention, comprises a longitudinally extending body member 2 having a pair of cylindrical portions 3 arranged integrally therewith with their axes aligned angularly relative to each other and a semi-cylindrical portion 4 arranged to one side of the cylindrical portions 3 for attaching the assembly to the cable in a manner hereinafter to be described.

There is arranged in the outer end of each 3 of the cylindrical portions 3, preferably a cylindrical-shaped socket portion 5, which cylindrical-shaped socket portions 5 have their axes disposed angularly relative to each other and to the axis of the wire cable with which the assembly is to be used.

40 There is disposed in each of the socket portions 5 preferably a cylindrical reflector button lens 6 which is held therein in any suitable manner but preferably forced thereinto and held therein solely by frictional forces. The reflector

45 buttons 6 are of the well known type and preferably have an annular flange 7 arranged there-around intermediate the length thereof which is adapted to cooperate with the inner walls of the socket portions 5 to frictionally hold the reflector button in position therein. A reflector button assembly which is preferably for use with the present invention is shown in the Brickman et al. Patent No. 2,274,661. The extreme rear portion of the reflector button is preferably coated with an aluminous paint or other suitable reflecting

matter as is well known to those skilled in the art.

The semi-cylindrical portion 4 is preferably made integral with the cylindrical portions 3 and there is arranged on the inner side thereof preferably a plurality of helical-shaped grooves 8 which conform to the contour of the lay of the strands of the wire rope cable with which the assembly is to be used. There is provided a complementary or cap member 9 similar to the semi-cylindrical portion 4 and having similarly shaped grooves 10 arranged in the inner surface thereof.

The improved safety reflector assembly of my invention is mounted on the wire rope cable of the guard rail in any desired position in the following manner:

The body member 2 is first positioned on the cable so that the helical-shaped grooves 8 on the inner side of the semi-cylindrical portion 4 properly fit the lay of the strands with the individual strands of the cable lying in the grooves with the cylindrical portions 3 together with the reflector buttons 6 carried thereby preferably disposed below the cable. The complementary or cap member 9 is then positioned on the opposite or back side of the cable opposite the body member with the strands on that side of the cable disposed in the grooves 10 arranged on the inner side of the cap member. A bolt, screw, or preferably a drive pin 12 is then inserted through aligned holes 13 and 14 in the center of the body member and the cap member respectively, so as to securely hold the body member and the cap member around the wire rope cable and the assembly securely in engagement therewith.

It will be seen that the providing of grooves 8 and grooves 10 in the inner sides respectively of the body member and the cap member will prevent the twisting of the assembly around the cable and the displacement of the assembly thereon so that the assembly will be maintained in its proper position at all times.

It will be also seen that by disposing the socket portions 6 and the reflector buttons 8 arranged therein angularly relative to each other, the reflector buttons will be clearly visible from any point on the highway to those travelling therewith in either direction, which is a decided advantage over any safety button reflector assembly heretofore proposed or used. It will be understood further that any number of the safety reflector assemblies of the present invention may be mounted along the guard rail at the most desirable points.

While I have shown and described one embodiment of my invention, it will be understood that I do not wish to be limited exactly thereto, since various modifications may be made without departing from the scope of the invention, as defined in the appended claims.

I claim:

1. A safety reflector assembly for highway guard cables comprising a body member having means arranged at each end thereof for receiving and housing a reflector button, a reflector button positioned at each end of said body member in the housing means carried thereby, an attaching portion carried by said body member having a plurality of grooves arranged therein conforming to the contour of the guard cable with which the assembly is to be used, and a removable complementary member which is adapted to cooperate with said attaching portion to securely attach the assembly to a guard cable so as to prevent twisting of the assembly thereon.

2. A safety reflector assembly for highway guard cables comprising a body member having a reflector button receiving portion arranged in each end thereof with the axes of said reflector button receiving portions arranged angularly relative to each other, a reflector button securely arranged in each of said reflector button receiving portions, an attaching portion carried by said body member having a plurality of grooves arranged therein conforming to the contour of the guard cable with which the assembly is to be used, and a removable complementary member which is adapted to cooperate with said attaching portion to securely attach the assembly to a guard cable so as to prevent twisting of the assembly thereon.

3. A safety reflector assembly for highway guard cables comprising a body member including two substantially cylindrical portions having their axes arranged angularly relative to each other and in substantially the same plane, each of said cylindrical portions having a socket portion arranged in the outer end thereof, a reflector button securely arranged in each of said socket portions, a substantially semi-cylindrical attaching portion arranged integrally with said cylindrical portions and substantially parallel thereto, said semi-cylindrical portion having a plurality of helical-shaped grooves arranged on the inner side thereof which conform substantially to the lay of the strands of the cable with which the assembly is to be used, and removable means cooperating with said semi-cylindrical attaching portion to securely attach the assembly to a guard cable and to prevent the assembly from twisting thereon.

4. A safety reflector assembly for highway guard cables comprising a body member including two substantially cylindrical portions having their axes arranged angularly relative to each other and in substantially the same plane, each of said cylindrical portions having a socket portion arranged in the outer end thereof, a reflector button securely arranged in each of said socket portions, a substantially semi-cylindrical attaching portion arranged integrally with said cylindrical portions to one side thereof and substantially parallel thereto, said semi-cylindrical attaching portion having the inner surface thereof conforming to the contour of the guard cable with which the assembly is adapted to be used, a removable complementary member having a similar inner surface which is adapted to cooperate with the semi-cylindrical attaching portion to securely attach the assembly to a guard cable and to prevent the assembly from twisting thereon, and means for securely holding the complementary member and said semi-cylindrical attaching portion together.

5. A safety reflector assembly for highway guard cables comprising a body member consisting of a substantially cylindrical-shaped portion having a socket portion arranged in each end thereof with the axes of said socket portions arranged angularly relative to each other, a reflector button arranged in each of said socket portions, an attaching portion carried by said cylindrical-shaped portion and arranged to one side of said socket portions, a removable complementary member which is adapted to cooperate with said attaching portion for securely attaching the assembly to a guard cable and to prevent the twisting of the assembly thereon, and a drive screw arranged through the complementary mem-

ber and the attaching portion for securely holding the same together.

6. A safety reflector assembly comprising a substantially cylindrical-shaped portion having a socket portion arranged in each end thereof with the axes of said socket portions arranged angularly relative to each other in substantially the same plane, a reflector button securely arranged in each of said socket portions, a semi-cylindrical-shaped attaching portion carried by said cylindrical-shaped portion to one side thereof and substantially parallel thereto for affixing the assembly to a highway cable or the like, a removable complementary member arranged opposite said attaching portion with which it is adapted to cooperate to securely affix the assembly in position on a cable, and means for securely holding the complementary member and the attaching portion in engagement with each other so as to provide a compact assembly unit.

7. A safety reflector assembly comprising a substantially cylindrical-shaped portion having a socket portion arranged in each end thereof with the axes of said socket portions arranged angularly relative to each other in substantially the same plane, a reflector button securely arranged in each of said socket portions, a semi-cylindrical-shaped attaching portion carried by said cylindrical-shaped portion to one side thereof and substantially parallel thereto, said semi-cylindrical-shaped portion having a plurality of helical-shaped grooves arranged on the inner side thereof of which conform substantially to the lay of the strands of the cable with which the assembly is adapted to be used, a removable substantially semi-cylindrical-shaped complementary member arranged opposite said last mentioned portion with which it is adapted to cooperate to securely affix the assembly in position on the cable and

to prevent the assembly from twisting thereon, and means for securely holding the complementary member and said semi-cylindrical portion in engagement with each other.

8. A safety reflector assembly comprising a substantially cylindrical-shaped portion having a socket portion arranged in each end thereof with the axes of said socket portions arranged angularly relative to each other in substantially the same plane, a reflector button securely arranged in each of said socket portions, a semi-cylindrical-shaped attaching portion carried by said cylindrical-shaped portion to one side thereof and substantially parallel thereto, said semi-cylindrical-shaped portion having a plurality of helical-shaped grooves arranged on the inner side thereof which conform substantially to the lay of the strands of the cable with which the assembly is adapted to be used, a removable substantially semi-cylindrical-shaped complementary member arranged opposite said last mentioned portion with which it is adapted to cooperate to securely affix the assembly in position on the cable and to prevent the assembly from twisting thereon, said complementary member having similar grooves arranged on the inner side thereof, and means for securely holding the complementary member and said semi-cylindrical portion in engagement with each other.

9. A safety reflector assembly for highway guard cables as defined in claim 8 wherein the means for securely holding the complementary member and the semi-cylindrical portion of the body member together in engagement with each other consists of a drive screw arranged centrally through both the complementary member and the semi-cylindrical portion.

ALAN E. BRICKMAN.
